United States Patent Office

Des. 203,785
Patented Feb. 15, 1966

203,785

PORTABLE HEATER

Edward H. Meisner, 215 Dumont Ave., Dumont, N.J.

Filed Sept. 18, 1964, Ser. No. 31,776

Term of patent 14 years

(Cl. D81—10)

FIG.1

FIG.3

FIG. 1 is a perspective view of a portable heater showing my new design;

FIG. 2 is a side elevation view thereof, the support being in folded position; and,

FIG. 3 is a front elevation view thereof, the support being in folded position.

The dominant features of my design reside in the portions shown in full lines.

I claim:

The ornamental design for a portable heater, as shown and described.
